UNITED STATES PATENT OFFICE

JOHN D. HILLIARD, OF SCHENECTADY, NEW YORK, ASSIGNOR TO GENERAL ELECTRIC COMPANY, A CORPORATION OF NEW YORK

ELECTRICAL TRANSMISSION DEVICE

Application filed June 10, 1929. Serial No. 369,904.

My invention relates to circuit breakers, and more particularly to circuit breakers of the fluid break type having a comparatively large interrupting capacity.

In oil circuit breakers of the type adapted for interrupting currents at high potentials, there are developed by the power arc during interruption of the circuit, large quantities of gases which project a portion of the oil body upwardly with great force against the cover structure to cause high, sudden, internal pressures within the circuit breaker housing. It is generally true that the interrupting capacity of an oil switch depends upon the strength of the switch housing to withstand these large and violent internal pressures without mechanical failure. In addition to these pressures, due to the sudden generation of gases by the action of the power arc on the oil or other arc extinguishing medium, a secondary explosion may be caused by a spark coming into contact with the inflammable gases in the upper part of the switch housing, as, for example, by a spark from the leads of the current transformer which is generally disposed adjacent one of the contactor studs and carried by the switch cover structure. Notwithstanding the ability of the switch housing to withstand these internal explosions, one or more of the conductor insulators supported by the housing, which generally comprise a bushing member of ceramic material as porcelain or the like, may be subjected to violent stresses by vibrations set up in the cover structure upon occurrence of these sudden pressures or explosions. Due to the fact that the insulating bushing is generally of brittle material, having considerable mass and radius of gyration, these vibrations may be of such order of magnitude as to cause fracture and consequent failure of the bushing.

An object of my invention is to provide a mounting structure for the insulating bushing, of such character that transmission of shock between the switch housing proper and the insulating bushing is substantially reduced or eliminated.

Another object of my invention is to pro-

vide means for preventing the above described secondary explosion within the breaker housing by isolating the current transformer structure from the gas-containing space in the upper portion of the breaker housing. 55

For a better understanding of my invention, reference may be had to the following description taken in connection with the accompanying drawing, in which the single figure is a view partly in section of one embodiment of my invention.

An oil circuit breaker of a well known type is partially illustrated and comprises by way of example an outer shell, or tank 1, containing an arc extinguishing medium 2, as an oil bath within which is immersed a movable contact or bridging member 3 co-acting with a so-called "explosion chamber", 4, in the usual manner. The upper portion of tank 1 has mounted thereon in any suitable manner 65 a metallic cover structure 5 of steel for example adapted to support and position a lead-in conductor stud (not shown), and its associated insulating bushing 6, which is generally composed of porcelain or other hard 70 and comparatively brittle material. The insulating bushing 6 is secured at 7, as by cement, to an annular flange 8, likewise suitably secured, as by bolts 9, to a supporting plate-like member 10, having an annular 75 depending flange 11 for a purpose herein-after described.

Mounted upon the top of cover structure 5 is an annularly flanged member 12, with respect to which member 10 is resiliently mounted for limited universal movement. To this end, cushioning material 13, comprising any suitable resilient aperiodic material, as for example rubber, cork board or equivalent, is interposed generally in the form of a gasket, 80 between members 10 and 12, so that there is no metal-to-metal contact between them. Due to the fact that the cover structure of the breaker is generally of steel, sudden large internal pressures acting thereon tend to cause 85 deformation or bulging of the same, with the result that the insulating bushing is forced out of its normal alignment.

In the mounting structure above referred to, the bushing is permitted a limited uni- 100

versal movement, i. e. axial and tilting movement, with respect to the cover structure, thereby greatly reducing stresses due to the above described pressures. Accordingly, vibrations or stresses set up in the cover structure 5 are not readily transmitted to the supporting member 10 to cause fracture of the bushing. Member 10 is clamped into position with respect to the cover structure by means of bolts 14 extending through the outer flanged portion of member 10, and secured to member 12. The bolts 14 co-act with metallic washers, or the like, spaced from member 10 by bushings 16, likewise of suitable resilient aperiodic material, thereby preventing transmission of shock to member 10 through its clamping structure while permitting limited universal movement of the bushing.

Disposed within the depending annular 20 flange 11, previously referred to, is a bushing current transformer 17 which is disposed in the usual manner around a conductor stud. The lower portion of the transformer housing is enclosed by a plate 18 secured to the 25 lower edge of flange 11, as by bolts 19, and to the lower edge of a metallic ring 20, secured and sealed as by cement 7' to bushing 6. In order to effect an hermetically tight joint, and to properly cushion the respective parts 30 suitably, aperiodic material 21 is interposed between plate 18 and the coil structure. The usual grounding shield 22 is secured, as by screw threaded engagement, to ring 20 to function in a manner well known in the 35 art.

The leads, (not shown), from the bushing transformer 17 are adapted to extend exteriorly of the cover structure through conduit 23. Accordingly, it will be noted that the 40 transformer structure is hermetically sealed with respect to the interior of the circuit breaker housing so that sparks from the leads to the current transformer, due to abnormal current conditions, are precluded from igniting the high inflammable gases which collect in the upper portion, or gas-containing 45 space, of the breaker housing upon interruption of the main circuit. Secondary explosions due to the ignition of these gases are 50 therefore materially reduced with resultant decrease of depreciation of the apparatus.

In the event of unusually violent internal 55 explosions within the circuit breaker housing, the shock, which would otherwise be transmitted directly to the more or less brittle insulating bushing 6, is materially absorbed by the aperiodic cushioning structure 13 and 16, so that the insulating bushing 4, which is of comparatively great mass and size, 60 is protected from mechanical failure due to the above mentioned causes.

It shall be understood that the terms "brittle" as used in the above specification and appended claims, is intended to include properties of the commonly used solid insulat-

ing materials which are capable of small deformation, as compared with steel, without fracture.

It shall be further understood that various changes in the structure illustrated may be made without departing from the spirit of my invention; for example, members 8 and 10 may comprise a single integral mounting plate, if desired, in which event the transformer housing structure is disposed above instead of beneath the upper portion of the circuit breaker housing, thereby obviating the necessity of further sealing.

What I claim as new and desire to secure by Letters Patent of the United States is:

1. The combination with a metallic circuit breaker housing and insulating structure of brittle material supported thereby, of cushioning means interposed between said housing and structure for substantially precluding transmission of shock from said housing to said structure.

2. The combination with a steel circuit breaker housing and an insulating bushing of brittle material supported thereby, of aperiodic means interposed between said housing and bushing for substantially precluding transmission of vibration due to concussion from said housing to said bushing.

3. In a circuit breaker of the type evolving quantities of gases during interruption of the circuit, the combination with housing structure and insulating structure supported thereby, of resilient shock absorbing means interposed between said structures for preventing failure of said insulating structure.

4. The combination with an oil circuit breaker comprising an oil containing receptacle within which contact structure is disposed, steel cover structure for said receptacle and a conductor insulating bushing of brittle material mounted on said cover structure, of shock absorbing means interposed between said cover structure and insulating bushing for substantially precluding transmission of vibration from said cover structure to said bushing.

5. The combination with an oil circuit breaker comprising a main housing, cover structure for said housing and an insulating bushing of brittle material mounted on said cover structure, of means resiliently mounting said bushing to permit limited universal movement of the same with respect to said cover structure comprising a supporting member secured to said bushing, aperiodic means interposed between said supporting member and cover structure, and means resiliently clamping said supporting member to said cover structure.

6. The combination with a circuit breaker of the type evolving combustible gases during interruption of the circuit, comprising a housing having a gas-containing space in the

upper part thereof, and transformer structure mounted on said housing and within said gas-containing space, of means hermetically sealing said transformer structure with respect to said gas-containing space.

5. 7. In an oil circuit breaker comprising housing structure having a gas-containing space in the upper part thereof and an insulating bushing mounted on and extending through said housing, the combination of a supporting member secured to said bushing, aperiodic means interposed between said member and housing structure so that relative movement between said housing and supporting member is permitted, transformer structure mounted on and depending from said supporting member into said gas-containing space, and enclosing means hermetically sealing said transformer structure from 20 gases evolved within the circuit breaker housing.

8. In an oil circuit breaker comprising a metallic housing structure and an insulating bushing of brittle material mounted thereon, the combination of a supporting plate-like member rigidly secured to said bushing, a gasket of yielding aperiodic material disposed between said plate-like member and housing structure permitting limited universal movement of said bushing with respect to said housing, and clamping members yielding urging said plate-like member into firm seating engagement with said gasket.

In witness whereof, I have hereunto set my hand this sixth day of June, 1929.

JOHN D. HILLIARD.
